UNITED STATES PATENT OFFICE.

JOSEPH SMITH, OF LOAMI, ILLINOIS, ASSIGNOR TO JOHN W. GREY, OF MAXWELL TOWNSHIP, SANGAMON COUNTY, ILLINOIS.

CHURN.

No. 856,187.

Specification of Letters Patent.

Patented June 4, 1907.

Application filed July 12, 1906. Serial No. 325,873.

To all whom it may concern:

Be it known that I, JOSEPH SMITH, a citizen of the United States, residing at Loami, in the county of Sangamon, State of Illinois, have invented certain new and useful Improvements in Churns; and I do hereby declare the following to be a full, clear, and exact description of the invention, such as will enable others skilled in the art to which it appertains to make and use the same.

This invention has relation to churns of the rotary class that may be operated by hand or power.

It is the object of the invention to provide a simplified construction having an enhanced efficiency to a degree that butter will not only be made very much quicker than by churns of common construction, but the cream or milk will be so thoroughly agitated or beaten that the separation of the serous parts of the mass from the other portion or portions will be, to all intents and purposes, complete so far as can be ascertained from the operation of the churn—a second churning producing nothing in the way of butter.

The invention consists of an organization characterized by several peculiar parts and features that are shown in the drawings, and that will be described in view of the same and pointed out with particularity in the concluding claims.

Of the said drawings, Figure 1 is a vertical longitudinal sectional view of my improved churn. Fig. 2 is a horizontal sectional view taken in the plane of the axis of the crank and the vertical bevel gear operated by it, looking down upon the churn. Fig. 3 is also a transverse sectional view through the parts just above the step of the rotary shaft, near the bottom of the machine. Fig. 4 is a sectional detail view, showing how the cover is secured in place. Fig. 5 is a detail view, showing the angular relationship of the dashers with their respective shafts whereby one set of dashers will tend to force the cream upward and the other downward.

Similar figures of reference designate the same parts or features, as the case may be, wherever they occur.

50 In the drawings, 10 designates the body of the churn that may be cylindrical or nearly

so, it being a little larger in diameter at the top than at the bottom, or vice versa, in order to tighten steel hoops thereon, as is understood by those skilled in the art.

55

11 is the bottom secured in place, as is common. In the bottom is secured a suitable step 12 for the foot 13 of the shaft or spindle 14 carrying the lower flights or dashers 15, and provided centrally with a shoulder 16 for the bottom bearing of the reversely 60 rotary sleeve shaft 17 that is provided with the upper flights or dashers 18.

19 is a cover for the churn consisting of a flat disk with a central opening for the sleeve 65 shaft 17 and its inclosed shaft 14 and affording a bearing for the crown bevel gear 19 secured to the sleeve shaft 17, and for the bracket 20 provided with suitable bearings for the horizontal shaft 21 to which the 70 crank 22 is attached. On the inner end of the crank shaft 21 there is a bevel pinion 23 that meshes with the bevel gear 19' and the reversely arranged bevel gear 23' on the top of shaft 14, by which the latter is driven 75 when the crank is turned, in a direction opposite to that in which the bevel gear 19' is operated.

The cover 19 is provided on its edge with horizontally projecting pins 24 that are disposed to enter holes 25 formed in the upper loose ends of springs 26 secured to the side of the churn and extending above its top, as shown.

The crank 22 may be placed on the squared 85 end of the shaft 21, the crank being provided with a similarly shaped hole to receive it, and a nut 21' may be secured on the threaded end of the shaft 21 to receive the crank as will be understood. This construction, in most 90 cases, is better than screwing the crank on the end of the shaft 21, as artisans will understand.

In use the shaft 14 and sleeve shaft 17 will be fitted in place with their bevel gears 23' 95 and 19' attached thereto, all as has been explained. The shaft 14 will have its foot stepped in the removable bearing 12, and the sleeve shaft 17 will rest at its bottom on the collar 16 on the said shaft 14. By the rotation of the crank, under these circumstances, the paddles of dashers 15 and 18 will be oper-

100

ated in different directions, and as all of the dashers are arranged on the shaft and sleeve at the same angle or inclination to their axes and secured at regular intervals from the top 5 to the bottom of the churn, it follows that as the shaft and sleeve are rotated in opposite directions the dashers on the sleeve will tend to force the cream downward, while those below, fixed to the shaft will tend to raise the 10 cream or force it upward, creating counter currents and an increased agitation of the mass is effected by the meeting of the two opposed currents, besides the action is such as to assist in the union of the molecules of 15 the serious matter so fast as butter is formed. Of course, the axial inclination of the paddles or flights 15 and 18 will be slight and not so abrupt as to impede the operation of the machine or secure the specified results 20 aimed at.

The step 12 is arranged so that it can readily be taken out in the cleansing of the churn and washed; and, besides, it will not be made of corrosive material or of a substance that 25 might prove harmful to the cream in the churn.

The dashers will be provided with as many and as large or small openings therethrough as may be considered best and conduce to the 30 easiest and best operations of the machine.

The arrangement of the dashers on the sleeve and shaft at regular intervals from the top to the bottom of the churn and at the same angle or inclination or with the same 35 obliquity to the axes of the sleeve or shaft, whereby counter currents are created in the cream in the churn and thorough agitation of

the cream is secured, is an important feature of the invention.

The simple arrangement for securing the 40 lid on the churn is such as to provide a tight connection with it and the top of the churn body so that cream will not leak through between the parts and yet secure a means of quick removal or partial removal of the cover 45 to examine the progress of the churning and the replacement of the latter.

What is claimed as the invention, is:—

A churn embodying in its construction a cylindrical body, a centrally disposed shaft 50 provided with a collar, a step upon which the shaft rests, a sleeve shaft surrounding the first-mentioned shaft and resting at its bottom on the said collar, each of the said shafts being provided with a plurality of pairs of paddles 55 or dashers the paddles of each pair being set obliquely to the axes of the shaft and sleeve and arranged at regular intervals on the shaft and sleeve from the top to the bottom thereof and on diametrically opposite sides of the said 60 shafts, whereby one plural set of dashers may tend to force the cream downward and the other plural set will tend to force it upward or in a reverse direction creating counter currents meeting at the longitudinal center of 65 the churn, and means for operating the said shafts, substantially as set forth.

In testimony whereof, I affix my signature, in presence of two witnesses.

JOSEPH SMITH,
